[57] CLAIM

The ornamental design for a fish hook knot tying device, as shown and described.

DESCRIPTION

FIG. 1 is a perspective view of a fish hook knot tying device embodying my new design.

FIG. 2 is a side elevational view.

FIG. 3 is a top plan view.

FIG. 4 is a bottom plan view.

FIG. 5 is a right end elevation as viewed in FIG. 2.

FIG. 6 is a left end elevation as viewed in FIG. 2.

The broken line showing of the line and hook in FIG. 1 is for illustrative purposes only and form no part of the claimed article.

FIG-1.FIG-5.FIG-2.FIG-6.FIG-3.FIG-4.
